INDIVIDUAL TOOTHBRUSH AND TOOTH
CLEANSER SERVICE PACKAGE

Thomas P. Darmody, Waterbury, Conn.

Application August 4, 1939, Serial No. 288,313

19 Claims. (CL 132—84)

One object of this invention is the provision of a package adapted to be sold or dispensed in vending machines, and consequently small and compact in size, to contain toilet articles, specifically a toothbrush and a container of tooth paste or tooth powder. The toothbrush and the container would both be of inexpensive manufacture so that they could be sold for a small sum such as can be represented by a common coin. 5
The packages would be small enough so that they might be conveniently carried in a lady's purse or a man's pocket. The articles contained within the package are entirely and hermetically sealed, so that they may be considered sterile 10 and therefore should meet with no objections on sanitary grounds from the general public.

Another object of the invention is the provision of such a package or container wrapped or covered with a transparent material such as 20 Cellophane, a material which is strong, moistureproof and transparent so that the articles contained within the package may be readily seen by the purchaser before opening the same.

The above and other objects will become apparent in the description below, in which characters of reference refer to like-named parts in the accompanying drawing which forms a part hereof.

Referring briefly to the accompanying drawing,

Figure 1 is a top view, partly in section, of a package of the kind mentioned, in the form of a bag.

Figure 2 is a cross-sectional view taken on the line 2—2 of Figure 1.

Figure 3 is a side view of the bag of Figure 1.

Figure 4 is a perspective view of a package of the kind mentioned, in the form of a box.

Figure 5 is a cross-sectional view taken on the line 5—5 of Figure 4.

Figure 6 is a view similar to Figure 5, but illustrating a modified form of construction within the box.

Referring in detail to the accompanying drawing, the numeral 10 represents a bag having the flap 11 by means of which the bag may be closed or sealed. Glue may be used for the purpose of sealing the bag, or staples, or any other desirable suitable means. The material 50 of the bag 10 is preferably Cellophane. The two sides of the bag 10 are indicated by the numerals 12 and 13, the former being the top side in Figure 1.

The toothbrush 14 and the paste tube or tooth powder container 15, are placed in the bag

against the lower side 13, preferably at an angle to the edges of the bag. A sheet 16 of transparent material such as Cellophane, is placed above the toothbrush 14 and the container 15, with the latter two articles between the sheet 16 5 and the bottom side 13 of the bag. Both sides of the sheet 16 are depressed against the side 13 of the bag, as is also the intermediate portion between the articles 14 and 15, and secured to the side 13 of the bag by means of glue 17 10 or the like. The top and bottom portions of the sheet 16 which extend beyond the extremities of the articles 14 and 15 are likewise glued to the bag side 13. Thus the hermetic sealing of the articles 14 and 15 within the bag 10 is as- 15 sured independently of the flap 11.

In the case where a box is used as a package instead of a bag, as shown in Figures 4, 5, and 6, a box made of cardboard or other suitable material is provided, as shown at 18. The box 18 20 comprises the bottom 19 and the four peripheral walls 20, the top of the box being open. A sheet of Cellophane is tightly wrapped around the finished box to form a transparent sealing cover 23, whose flaps are glued to the box in a common fashion. The articles 14 and 15 are secured against the bottom 19 of the box by means of wire staples 21 whose yokes 22, outside the bottom 19, lie between the latter and the cover 23. 30

In the modified form of the box package, as shown in Figure 6, a sheet 24, similar to the sheet 16, is similarly secured to the bottom 19 around the articles 14 and 15, by means of glue 25. Thus the sheet 24 not only secures the 35 articles 14 and 15 to the bottom 19, but it also hermetically seals them within the box, in the same manner as the sheet 16 in the case of the bag 10. If desired, the wire staple form of securing the articles 14 and 15 may also be used 40 with the bag 10, or a combination of both forms may be used with both the box and the bag. Obviously, other modifications in form and structure may be made without departing from the spirit and scope of the invention. 45

As the packages described may be used for other articles than the toothbrush and tooth cleanser container mentioned, where a sanitary sealing of the articles within the package is desired, it is not desired to limit the application 50 of the package to toothbrushes and tooth cleanser containers.

I claim:

1. A package of the class described comprising a sealed container having a top wall and 55

- a bottom wall, said container being formed of Cellophane or the like, a toothbrush and a tooth cleansing agent container mounted within said package against said bottom wall, and means for 5 securing and sealing said brush and cleansing agent container against said bottom wall.
2. A package of the class described comprising a sealed container having a top wall and a bottom wall, said container being formed of 10 transparent material, a toothbrush and a cleansing agent container mounted within said package against said bottom wall, a sheet of transparent material mounted above said brush and cleansing agent container, said sheet having its 15 edges and its intermediate portion pressed against said bottom wall and secured thereto, said intermediate portion of said sheet dividing said brush and cleansing agent container into separate compartments sealed from each other 20 and from the upper wall of said package.
3. A package of the class described comprising a sealed Cellophane bag having a top wall and a bottom wall, a toothbrush and a cleansing agent container mounted against one of said 25 walls, and means for retaining and sealing said toothbrush and container against said wall.
4. A package of the class described comprising a sealed Cellophane bag having a top wall and a bottom wall, a toothbrush and a cleansing 30 agent container mounted against one of said walls, and means for retaining said toothbrush and container against said wall comprising a sheet of Cellophane having its peripheral edge secured to said wall, said peripheral edge surrounding said toothbrush and container.
5. A package of the class described comprising a sealed Cellophane bag, a toothbrush and cleansing agent container contained within said bag, and means for securing and sealing said 40 toothbrush and container against one of the sides of said bag.
6. A package of the class described comprising a sealed Cellophane bag, a toothbrush and cleansing agent container contained within said bag, and means for retaining said toothbrush and container against one of the sides of said bag comprising a sheet of Cellophane having its 45 peripheral edge secured to said side, said peripheral edge surrounding said toothbrush and container.
7. A package of the class described comprising a sealed Cellophane bag, a toothbrush and a cleansing agent container mounted in said bag in mutually spaced-apart relationship, and means for retaining said toothbrush and container against one of the sides of said bag comprising a sheet of Cellophane having its peripheral edge secured to said side, the intermediate 55 portion of said sheet between said toothbrush and container being also secured to said side.
8. A package of the class described comprising a box open at the top, a Cellophane wrapper sealed about said box and forming a closure of said open top of the box, a toothbrush and a 60 cleansing agent container mounted in said box in spaced-apart relationship, and means for securing and sealing said toothbrush and container against the bottom of said box in said spaced-apart relationship.
9. A package of the class described comprising a box open at the top, a Cellophane wrapper sealed about said box and forming a transparent closure of said open top of the box, a toothbrush and a cleansing agent container mounted 65 on the bottom of said box in mutually spaced- 70 apart relationship, and means for retaining and sealing said toothbrush and container against said bottom of the box in said relationship and for sealing said toothbrush and container from each other.
10. A package of the class described comprising a box open at the top, a Cellophane wrapper sealed about said box and forming a transparent closure of said open top of the box, a toothbrush and a cleansing agent container mounted on the 10 bottom of said box in mutually spaced-apart relationship, and means for retaining said toothbrush and container against said bottom of the box in said relationship and at the same time sealing said toothbrush and container against 15 the remainder of the compartment enclosed by the box and said transparent closure and from each other.
11. A package of the class described comprising a box open at the top, a Cellophane wrapper 20 sealed about said box and forming a transparent closure of said open top of the box, a toothbrush and a cleansing agent container mounted on the bottom of said box in mutually spaced-apart relationship, and means for retaining said 25 toothbrush and container against said bottom of the box in said relationship and at the same time sealing said toothbrush and container against the remainder of the compartment enclosed by the box and said transparent closure and also 30 sealing said toothbrush and container from each other.
12. A package of the class described comprising a sealed container having opposed walls, a toothbrush and a cleansing agent container 35 mounted therein, said toothbrush and said cleansing agent container being positioned in mutually spaced-apart relationship, means for securing said toothbrush and said cleansing agent container in said relationship against one 40 of said walls, and means for sealing said toothbrush and said cleansing agent container against said wall from the remainder of the compartment enclosed by said walls.
13. A package of the class described comprising a sealed container having opposed walls, a toothbrush and a cleansing agent container mounted therein in mutually spaced-apart relationship, means for securing said toothbrush and cleansing agent container in said relationship against one of said walls, and means for sealing said toothbrush and said cleansing agent 45 container against said wall from the remainder of the compartment enclosed by said walls and 50 from each other.
14. A package of the class described comprising a sealed container having opposed walls, one of said walls being transparent, a toothbrush and a cleansing agent container mounted therein in mutually spaced-apart relationship, wire 60 staples passing through the other of said walls and embracing said toothbrush and said cleansing agent container and securing the same in said relationship against said other wall, and a sheet of transparent material mounted against 65 said toothbrush and cleansing agent container and having its peripheral edge secured to said other wall, said toothbrush and cleansing agent container being thereby sealed between said sheet and said other wall.
15. A package of the class described comprising a sealed container having opposed walls, one of said walls being transparent, a toothbrush and a cleansing agent container mounted within 70 said container, means for securing said tooth- 75

brush and said cleansing agent container against said other wall, and a sheet of transparent material covering said toothbrush and cleansing agent material and having its peripheral edge sealed against said other wall.

- 5 16. A package of the class described comprising a sealed container having a top wall and a bottom wall, said container being formed of transparent material, a plurality of articles 10 mounted within said package against said bottom wall in spaced relation to each other, a sheet of transparent material mounted above said articles, said sheet having its edges and its intermediate portions between said articles 15 pressed against said bottom wall and secured thereto, said intermediate portions of said sheet dividing said articles into separate compartments sealed from each other and from the upper wall of said package.
- 20 17. A package of the class described comprising a sealed Cellophane bag having a top wall and a bottom wall, one or more articles mounted against one of said walls, and means for retain-

ing said articles against said wall comprising a sheet of transparent material having its peripheral edge secured to said wall, said peripheral edge surrounding said articles.

18. A package comprising a sealed container 5 having opposed walls, a toothbrush and a cleansing agent container mounted within said sealed container, means for securing said toothbrush and cleansing agent container against one of said walls, a sheet of transparent material 10 covering said toothbrush and cleansing agent container and having its peripheral edge sealed against said wall, the other of said walls being transparent.

19. A package comprising a sealed container 15 having opposed walls, one or more articles mounted within said container, means for securing said articles against one of said walls, a sheet of transparent material covering said articles and having its peripheral edge secured 20 against said wall, the other of said walls being transparent.

THOMAS P. DARMODY.
